CORSET

Joseph J. Kispert, Hamden, Conn., assignor to I. Newman & Sons, Inc., New Haven, Conn., a corporation of Connecticut

Application May 16, 1936, Serial No. 80,032

6 Claims.

(Cl. 2-27)

This invention relates to corsets, and has for an object to provide an improved construction wherein an inner vest structure is presented coacting with a pair of exterior flaps to secure a desired adjustment and desired fit without presenting an objectionable thickness.

Another object of the invention is to provide a wrap-around corset with a pair of front flaps and an inner vest connected through the use of 10 flat sliding straps or tapes whereby a desired adjustment may be secured without adding appreciably to the thickness of the garment.

An additional object of the invention is to provide a corset having a vest and front flaps and 15 elastic members connecting the adjacent edges of the flaps to the front edges of the corset body independent of the vest.

An additional and further object is to provide a construction wherein a covering flap is provided 20 at the front opening adapted to overlap part of the vest structure when the garment is in use and thereby prevent any protuberance of any portion of the body.

In the accompanying drawings:

25 Fig. 1 is a perspective view almost in front elevation disclosing a corset embodying the invention, one of the front flaps being thrown back for illustrating part of the vest and the connection between the vest and flap;

30 Fig. 2 is an enlarged fragmentary sectional view through Fig. 1 approximately on the line 2-2;

Fig. 3 is an enlarged fragmentary elevation of the connection between the front edge of the 35 corset, the vest and flap, said portions being broken away for better illustrating the construction;

Fig. 4 is an enlarged fragmentary view of the upper part of the corset shown in Fig. 1 illustrating the comparative size of the sliding straps and adjacent parts;

Fig. 5 is an enlarged fragmentary sectional view through Fig. 3 approximately on the line 5-5;

45 Fig. 6 is a view similar to Fig. 1 but showing a slightly modified construction wherein elastic connects the front edge portion of the vest with the lower front edge portion of the corset body;

50 Fig. 7 is a view also similar to Fig. 1 but showing a second modified form of the invention wherein the elastic has been eliminated and straps substituted;

Fig. 8 is a view similar to Fig. 7 but showing 55 a modified structure thereof;

Fig. 9 is a view similar to Fig. 5 but illustrating a section through Fig. 8 on line 9-9.

Referring to the accompanying drawings by numerals, 1 indicates the body of the corset which has a back 2 and side portions 3 and 4, 5 said side portions having front edges 5 and 6. Front sections or strap covering flap members 7 and 8 merge into the sides 3 and 4 and form in a certain sense continuations of these sides. As illustrated in the drawings, and particularly 10 in Fig. 2, the slide strap covering member 7 is at least one-half the effective length of the slide straps 15. The effective length of the straps 15 is from point 50 to point 51 as illustrated in Fig. 2. The slide straps 16 and associated parts are of 15 identical formation to the slide straps 15 and associated parts. Arranged between the front edges 5 and 6 is a vest 9 formed into two sections, 20 namely sections 10 and 11. These sections are connected by suitable disengageable fastening means 12 with the meeting edges of the sections centrally of the body of a person when the corset is in use. Coacting with the vest 9 are front 25 flaps 13 and 14 and connected to the side edges of the vest are suitable flat straps 15 and 16. These straps are strong fabric members and are flat so that when the garment is in use this connection will not produce an undesirable thickness.

The respective flaps 13 and 14 are provided with stay pockets 17 and 18 and elastics 19 and 20 are secured to the respective rear edges of these pockets and to the respective front edges of the covering members or flaps 7 and 8. Suitable eyelets 21 and 22 are provided in the lower part of the pockets 17 and 18 whereby these pockets may be pulled towards each other by suitable lacing and the elastics 19 and 20 stretched circumferentially. These two elastics are stretchable circumferentially and act to cause the lower part of the corset to snugly fit on and below the hip line of a person wearing the corset. The sections or covering flaps 7 and 8 are each preferably wider than the exposed parts of the respective straps 15 and 16. When the parts are in the position at the right of Fig. 1 these covering flaps will cover the opening between the respective rear edges of flaps 13 and 14 and the respective front edges of the sides 3 and 4. It is evident that if the straps 15 and 16 were made longer, sections 7 and 8 could be made wider, and if this was not desirable the covering flaps could be left the same width.

It will be understood that when the corset is first put on it is passed around the body and the fasteners 12 interlocked. The flaps 13 and 55

14 are then brought loosely in front of the vest 9 and lacing applied to the eyelets 21 and 22. This lacing is adapted to be pulled until a desired tension is secured at and below the hip line. 5 After this has been done the respective lacings 23 and 24 are applied to the respective hooks 25 and 26 for drawing the front edges of the flaps 13 and 14 towards each other. When this last action takes place the straps 15 and 16 will slide through the respective elongated openings 27 and 28 until there is an even strain between all of the parts including the flaps, the vest and the sides 3 and 4. After the lacings 23 and 24 have been properly placed or interlocked with 15 the hooks 25 and 26, the free ends are tied and the corset is therefore in the proper position on the user.

In order to provide a properly formed opening for the straps 15 and 16 and yet allow the same 20 to slide back and forth without tearing or injuring the parts, a special structure has been provided illustrated particularly in Figs. 2 to 5 inclusive. From these figures it will be observed that the side 3 is connected to a strip of fabric 25 29 which may have raw edges on each side and which is provided with slots 28' for accommodating the respective straps 15. As the structures on both sides are identical, the description of one will apply to both. As indicated in Fig. 2 30 the strap 15 extends through the openings 28 and 28' and is secured by suitable lines of stitching to the section 10 and to the flap 14. It will be noticed also that there is a stay and stay pocket 30 for reinforcing the section 10 and the 35 stay and stay pocket 31 for reinforcing the flap 14. In order to prevent a pull on the strap 15 tearing the strip 29 at opening 28', there is provided on each side of each opening a reinforcing member 32 which is a strap of strong fabric having its edges bent back as indicated at 33 and 34 in Fig. 5. The edges of this strip as indicated in 40 Figs. 3 and 5 extend from one opening 28 to the other opening whereby in a certain sense there are presented selvaged edges to the edges of the 45 various straps 15. Also in order to prevent tearing there is provided a strip 35 having its edges bent back as shown in Fig. 2, said strip extending over a large part of the various strips 32 and are stitched thereto by suitable lines of stitching 50 36 and 37. These lines of stitching also extend through the reinforcing stay pocket 33 which carries the steel or stay 38' and a covering strip 39 which is also bent back at 40. In this way a thickened portion having rounded 55 edges is presented adjacent the openings 28 and 28'. The parts have been greatly exaggerated in Fig. 2 to illustrate how these edges take up the strain rather than the edges of opening 28'. It will be noted that the respective strips 32 extend 60 beyond opening 28' and are secured by suitable stitching 41 to the bent back edge portion 42 of side 3 and also the stay pocket 43. This arrangement is carried out from the top of the corset down to the respective elastic members 19 and 20 and thereby provides a construction 65 whereby the straps 15 and 16 may freely slide while in a flat condition, thus maintaining the structure at this point as thin as possible. It will also be noted that the vest 9 is naturally 70 beneath the front flaps and that the hose supporters 44 and 45 are connected respectively to the lower ends of the pockets 17 and 18, whereby when these hose supporters are in use proper tension is provided to prevent any upward movement of the corset. It will be noted that the 75

steel or stay 38' is alongside the various elongated or rectangular openings 28 so as to prevent any distortion or spreading of these openings when strain is exerted on straps 15. It will also be noted that the covering flaps 7 and 8 are amply wide to prevent any of the flesh of the user protruding through the openings between the straps 15. Usually when the corset is in use the straps 15 pull the rear edges of the vest 9 beneath or 10 interiorly of the covering flaps 7 and 8.

In Fig. 6 a slightly modified construction is shown to that illustrated in Fig. 1. The same reference numerals will be used in this figure as in Fig. 1 except for the modified parts. In this form of the invention the vest 9' has the respective sections 10' and 11' which extend slightly less than the full length of the corset. Forming the lower part of the respective sections 10' and 11' are substantially circumferentially stretchable elastic members 46 and 47. One edge of the 20 elastic member 46 is secured to the section or covering flap 7 and one edge of the elastic member 47 is secured to the section or covering flap 8, while the other edges are secured to the respective pockets 48 and 49, said pockets extending for the full length of the vest and having the hose supporters 44 and 45 secured thereto. In this form of the invention the flaps 13 and 14 are cut away at the lower ends so as to taper similar to the lower part of the vest in Fig. 1, and consequently the various straps 15 and 16 will extend 30 downwardly for about half the length of the respective flaps. Aside from these features the construction is the same as shown in Fig. 1 and 35 functions in the same manner.

In Fig. 7 a further modified form of the invention is seen, the same being similar to the structure shown in Fig. 1 except that the sections 10'' and 11'' extend for the full length of the front of the garment and also the flaps 13' and 14'. 40 The elastics 19 and 20 of Fig. 1 have been eliminated and the respective straps 15 and 16 positioned to extend from the top to the bottom of the garment. Aside from the structure just mentioned, the corset is the same as shown in Fig. 1 45 and functions in the same way.

Figs. 8 and 9 show a slightly modified structure to that illustrated in Fig. 7 in that the various straps 15 and 16 are grouped only at the upper part of the garment. At the lower part of the 50 garment there are provided groups 15' and 16' of flexible textile straps which are adapted to extend through the respective eyelets '15'' and '16''. In this form of the invention as well as the other forms set forth the respective sections 55 or covering flaps 7 and 8 are of sufficient width to close the opening between the edge of the flap and the edge of the vest. Also these covering flaps carry one or more steels or stays for stiffening purposes. At least one stay is provided 60 near the various openings 27 and 28 so that when a pull is brought to bear on any of the straps these openings will not become distorted or out of shape. In this way the straps are maintained flat as they function and thereby provide a desired sliding connection which will be of minimum thickness and which will automatically adjust the parts to equalize the strain. It will also be noted that the various straps as they extend 65 from the vest structure pass or rather extend 70 interiorly of the covering flaps and then through the various openings so that a pull on the front flaps 13 and 14 will have a tendency to pull the rear edges of the corset structure beneath the covering flaps.

I claim:

1. A corset including a body open at the front and provided adjacent the respective front edges with spaced apertures, a vest structure arranged interiorly of said body and normally extending across the front thereof, circumferentially positioned reinforcing strips of fabric carried by said body positioned between the respective apertures, said strips having their edges turned to produce a smooth surface adjacent the respective apertures, lines of stitching for securing said strips in place, a pair of front flaps acting as circumferential elongations of the front edge portions of said body, sliding straps extending through said apertures, the ends of said sliding straps being connected respectively to the vest and to the front flaps, said front flaps being provided with lacing receiving members whereby the front flaps may be drawn towards each other.
2. A corset including a body open at the front, said body adjacent each of its front edges having spaced openings spaced from the front edges, a circumferentially extending reinforcing strip of material arranged between each of said openings, a vest normally positioned between the two front edges of the corset, a pair of front flaps arranged in front of the vest, slide straps extending through said openings and connecting the flaps with the vest so that when the flaps are drawn towards each other tension will be brought to bear on the vest, means for receiving lacings for drawing the front edges of the flaps towards each other, and an elastic member associated with each front flap extending from near the front part of each front flap to the corset body, said elastic members extending from the lower edge of the corset body upwardly for less than half the height of the corset body.
3. A corset including a body open at the front, said body adjacent each of its front edges having spaced openings spaced from the front edges, a stay positioned alongside said openings to prevent the openings spreading when strain is brought to bear on the material carrying the openings, a circumferentially extending reinforcing strip of material arranged between each of said openings, a vest normally positioned between the two front edges of the corset, a pair of front flaps arranged in front of the vest, flat slide straps extending through said openings and connecting the

flaps with the vest so that when the flaps are drawn towards each other tension will be brought to bear on the vest, and means for receiving lacings for drawing the front edges of the flaps towards each other.

4. A corset including a body open at the front and provided adjacent the respective front edges with spaced apertures set back from said front edges, a vest structure arranged normally interiorly of said body and normally extending across the front thereof, circumferentially positioned reinforcing members of fabric carried by said body and positioned between the respective apertures, a pair of front flaps acting as circumferential elongations of the front edge portion of said body, slide straps extending through said apertures, the ends of said slide straps being connected respectively to the vest and to the front flaps, said front flaps being provided with means for disengageably fastening them together.

5. The corset as claimed in claim 4 wherein the vest structure is formed with circumferentially stretchable and elastic members at the lower part, each stretchable and elastic member having one end connected to the front part of said corset body and the other end connected to the vest near the center thereof.

6. A front lace corset having a body open at the front, a vest, a pair of front flaps acting as continuations of the front edges of said body, a row of slide straps connecting the rear edges of said front flaps to the side edges of said vest, said body along each front edge having a row of vertically spaced openings through which the respective straps slidably extend, said reinforced openings being set back from the respective front edges of said body at least one-half the effective length of said slide straps to define strap covering members to cover the openings between the rear edges of said vest and the front edges of said body, said straps being positioned to function to draw the rear edges of said vest beneath the respective strap covering members when the front edges of said flaps are drawn toward each other to make the corset conform to the size of the wearer, and means including lacings for drawing the front edges of said flaps toward each other.

JOSEPH J. KISPERT.
